US00D726892S

(12) **United States Design Patent**
Chan

(10) **Patent No.:** **US D726,892 S**
(45) **Date of Patent:** **** Apr. 14, 2015**

(54) **WATER COOLING FAN**

(71) Applicant: **Chia-Ming Chan**, Taichung (TW)

(72) Inventor: **Chia-Ming Chan**, Taichung (TW)

(73) Assignee: **Ya Suh Dar Ventilation Co., Ltd.**,
Taichung (TW)

(**) Term: **14 Years**

(21) Appl. No.: **29/480,052**

(22) Filed: **Jan. 23, 2014**

(51) LOC (10) Cl. **23-04**

(52) U.S. Cl.

USPC **D23/333; D23/351**

(57) **CLAIM**

The ornamental design for a water cooling fan, as shown and described.

DESCRIPTION

FIG. 1 is a perspective view of a water cooling fan showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is bottom plan view thereof; and,

FIG. 9 is a perspective view showing the water cooling fan in use.

The broken lines shown in FIGS. 4 and 5 depict parts of the water cooling fan that form no part of the claimed design. The broken lines shown in FIG. 9 illustrate environmental structure and form of the water cooling fan which forms no part of the claimed design.

1 Claim, 9 Drawing Sheets
